UNITED STATES PATENT OFFICE.

OTEY R. KIRKPATRICK, OF FORT WORTH, TEXAS.

MONKEY-WRENCH.

1,364,937.

Specification of Letters Patent. Patented Jan. 11, 1921.

Application filed December 16, 1919. Serial No. 345,309.

To all whom it may concern:

Be it known that I, OTEY R. KIRKPATRICK, a citizen of the United States, residing at Fort Worth, in the county of Tarrant and 5 State of Texas, have invented certain new and useful Improvements in Monkey-Wrenches, of which the following is a specification.

My invention relates to wrenches and 10 more particularly to monkey wrenches; and the object is to provide wrenches which can be instantly adjusted to any ordinary size nut and which has advantages over existing monkey wrenches and which is provided 15 with an improved adjustment whereby the wrench can be adjusted for different sizes of nuts by the same hand which is using the wrench and which is simple in construction and which can be easily and quickly ad- 20 justed to any required grasp and which may also be used as a pipe wrench. Other objects and advantages will be fully explained in the following description and the invention will be more particularly pointed out in the 25 claim.

Figure 1 is a side elevation of the wrench. Fig. 2 is an edge view of the same. Fig. 3 is a longitudinal section of the movable jaw and a broken section of the handle or power 30 arm and showing how the movable jaw is locked stationary for use. Fig. 4 is an elevation of the work end of the locking plunger. Fig. 5 is a side elevation of the wrench with the movable jaw provided with a shoe. 35 Fig. 6 is an edge view of the same.

Similar characters of reference are used to indicate the same parts throughout the several views.

This invention includes a handle or power 40 arm 1 having a stationary jaw 2 integral therewith. The wrench is also provided with a movable jaw 3 which has two yokes 4 and 5 which receive and move on the power arm 1. The yokes have openings to receive 45 the arm 1 and the yokes are preferably integral with the jaw 3. A portion of the power arm 1 is provided with teeth 6 and means are provided for locking the jaw 3 to the power arm 1. The jaw 3 has formed integral therewith a lock-carrying member 7 which has a chamber therein for a plunger 50 lock 8 which has teeth corresponding to the teeth on the power arm. A spring 9 holds the lock 8 in engagement with the power 55 arm. The teeth on the power arm have one shoulder or side of each tooth at right angles

to the power arm and the lock 8 has teeth which have one shoulder or side at right angles to the lock 8 so that the lock may be released from the power arm by a pull at 60 right angles to the power arm and another object in this construction is that the teeth of the lock will go directly into the teeth of the power arm. This will prevent the jaw 3 from receding from the object to be grasped. 65 The lock 8 is actuated for releasing by a pivoted lever 10 which is fulcrumed in a chamber 11 in the lock-carrying member 7. The lever 10 engages the lock 8 loosely by reason of the notch or recess in the side of 70 the plunger lock. The fulcrum pin 12 is inserted through the walls of the lock-carrying member.

The advantage of the construction shown herein is that the lock 8 does not rest on a 75 pivot pin during the strain, as in other wrenches. The lock bears against a solid bearing wall 13 of the lock-carrying member 7 when the jaw 3 is under strain and the flat surfaces of the teeth of the lock bear 80 against the flat surfaces of the teeth 6 of the power arm. At the same time the spring 9 is holding the teeth in engagement. The flat bearing wall 13 co-operates with the lock 8 to sustain the entire strain against the 85 movable jaw 3.

The variation shown in Figs. 5 and 6 includes a jaw 14 and a shoe 15 mounted thereon. In this form of the device, the shoe may be made of a different metal from 90 the power arm 1.

The movable jaw 3 has increased strength because it has the lock-carrying member 7 integral therewith, thus making a long bearing and the yoke 5 tends to keep the grip 95 surface at right angles to the handle 1. The lock 8 cannot be displaced because of the four walls of the cavity or chamber which retains the lock.

What I claim, is,—

A wrench of the type described, comprising a shank, a fixed outer jaw carried thereby, rack teeth formed upon the inner edge of said shank, a movable inner jaw and frame having a longitudinal opening there-through and slidably mounted on said shank, said frame having a recess therein rectangular in cross-section and extending at right-angles to the longitudinal axis of the shank, and from said longitudinal opening into said frame and one wall of said recess constituting a bearing wall, a ratchet 100

105

110

block rectangular in cross-section slidable in said recess and guided by the walls thereof with the teeth of the block maintained in position to engage the shank teeth for coöperating with said bearing wall to sustain the strain on said movable jaw, said block having a side notch, a spring within said recess seated against the bottom of said recess and normally engaging said ratchet block to hold the same in engagement with the shank teeth, said jaw frame having an opening therein extending from said recess toward

the handle of the wrench, and a lever pivoted within said opening and extending into the side notch of the ratchet block and normally standing idle and adapted to shift said block from engagement with the toothed shank and against tension of the spring, and provided with a handle in line with the handle of the wrench.

15
20
In testimony whereof, I set my hand, this fifth day of December, 1919.

OTEY R. KIRKPATRICK.
